UNITED STATES PATENT OFFICE.

LYONEL EDWIN CLARK, OF LONDON, ENGLAND.

FLOATING DOCK.

SPECIFICATION forming part of Letters Patent No. 731,858, dated June 23, 1903.

Application filed December 1, 1902. Serial No. 133,413. (No model.)

To all whom it may concern:

Be it known that I, LYONEL EDWIN CLARK, a subject of the King of Great Britain, residing at No. 11 Victoria street, London, S. W., England, have invented certain new and useful Improvements in Floating Docks, of which the following is a specification.

My invention relates to floating docks of the class which are self-docking—*i. e.*, those which are so constructed that each section may be raised for inspection or repair by other parts of the structure without the aid of divers or any separate structure or apparatus.

The object of my invention is to so improve floating docks of this class that the several sections while capable of being securely fastened together to form a rigid structure acting coincidentally to raise a vessel may be separated and two of the sections may be employed to lift the remaining section or any one of the remaining sections if there be more than three employed, and each section may, if desired, be employed to raise a small vessel.

In carrying out my invention I prefer to make each section of the dock of a general **U** shape in cross-section, as is commonly done, because this general construction is found to afford the greatest resistance to longitudinal strains. I may make the dock in three sections—viz., two terminal sections and a single central section—or I may employ two terminal and two or more central sections, each section being separable from the others when desired, but all capable of being rigidly secured together when placed to raise a vessel. Each of the central sections may be of the same general contour, and each such section is terminated at each end with a joint disposed in a vertical plane, by which it may be connected with its companion central sections or terminal sections. Each of the terminal sections, while for the most part of the same general contour as the central section, has its bottom portion prolonged at one end to form a tongue that is adapted to fit between the vertical side walls of any one of the other sections or to extend under one of the other sections. Each central section and each terminal section is a stable structure capable of doing its share in lifting a vessel or of itself lifting a relatively small vessel, and each is provided with its own pumping apparatus

and is capable of being lowered and raised independently of the others. Each terminal section is so proportioned and so constructed that it is made capable of lifting and supporting on its tongue portion a part—say one-half the weight—of the dock-section it is used to lift; but the two terminal sections in any event should be so constructed as to be able when working together to lift a central section clear of the water and hold it there. In like manner it should be so constructed that when employed in connection with a central section to raise the other terminal section it shall be capable of doing its share of the work.

As my invention does not contemplate any material change in the manner of forming the water-tight compartments or in the pumping apparatus, I have merely indicated in the accompanying drawings the general outline of a floating dock embodying my improvements.

Figure 1 shows a side elevation of such a floating dock comprising a single central section and two terminal sections. Fig. 2 is a plan view thereof. Fig. 3 is an end view of one of the sections. Fig. 4 is a side elevation, showing the arrangement of the sections when the terminal sections are employed to lift a central section clear of the water-line for inspection or repair. Fig. 5 is a plan view of the sections in the position shown in elevation in Fig. 4. Fig. 6 shows the arrangement of the sections when a terminal section and a central section are employed to raise the remaining terminal section. Fig. 7 is a plan view of the sections arranged as shown in elevation in Fig. 6. Fig. 8 is a detail view illustrating the manner of joining two adjacent sections.

In Fig. 1 I have shown two terminal sections A B and a single central section C. The central section is formed in the usual way, being of a general **U** shape in cross-section, as indicated in Fig. 3. It is provided with any number of water-tight compartments and carries suitable pumping apparatus and may be provided with any other machinery that is usually employed or that may be required. While I have shown a single central section, two or more of such sections may be employed, and they may be secured together at their ends

in the usual or in any suitable way. Each terminal section A B is similar to the central section C in most respects. Each of them is U-shaped in cross-section and each may be provided with water-tight compartments, pumping apparatus, &c. Any suitable means may be provided for detachably connecting each terminal section A or B with the opposite ends of the central section. When the several sections are thus connected, they form one rigid structure adapted to lift a vessel. The main difference between the terminal sections and the central section is that each terminal section has a tongue D projecting from its bottom portion and adapted to extend between the side walls of the central section in the manner indicated in Figs. 6 and 7 or to extend under any one of the other sections in the manner indicated in Figs. 4 and 5. The tongue portion may be of any suitable size and shape, provided that its dimensions are such that it may project wholly or partly into one of the other sections. Each terminal section is so arranged and the water-tight divisions are so disposed that it is capable of lifting and supporting on its tongue at least half the weight of the central section or any one of such central sections should the dock have more than one. Although the best and simplest arrangement of the terminal sections is one where each terminal section is so proportioned that it can lift and support at least one-half the weight of another section, I may of course so arrange the sections that one of them may carry more or less of the weight of the central section than the other, the essential feature of the design being that the two sections which are employed to lift another are capable, when working together, of lifting a third section entirely clear of the water and holding it there. As before stated, when the sections are employed to lift a vessel they are rigidly secured together in the manner indicated in Figs. 1 and 8. When it is desired to inspect or repair one or more of the sections, the fastening devices between the sections are removed. If there be more than one central section, the fastening between the several central sections are removed. When it is desired to raise a central section above the water-line, the terminal sections are turned around in the manner indicated in Fig. 4, so that their tongues face each other. They are sunk until their tongues are below the plane of the bottom of the central section, or the central section is pumped until its bottom is above the plane of the tongues. Then the tongues are made to project under the central section, and the terminal sections are then

pumped until they rise sufficiently to lift the central section clear of the water-line in the manner indicated in Fig. 4. When it is desired to raise a terminal section, the tongue of such terminal section is made to project 65 into the central section, as indicated in Fig. 6, and the tongue of the other terminal section is made to project under the opposite end of the terminal section to be raised, and then the sections are pumped in the usual 70 manner until the terminal section to be inspected or repaired is raised above the water-line to a sufficient extent.

A dock constructed in accordance with my invention is self-docking in every respect, 75 while the means for accomplishing this result are very simple. When the sections are secured together in position for raising a vessel, they all form continuations of the same general structure and have the same general 80 outline. The tongue on each terminal section is a continuation of the lower portion or pontoon of such section, and its deck is in the same plane as the deck of such pontoon, and therefore when the three or more sections are 85 bolted together their decks form one continuous plane. When a terminal section is used in connection with a central section to raise the other terminal section, the deck of the tongue of the raising section is brought into 90 line with the deck of the central section used to support and raise the opposite end of the raised terminal section. This is also true when two terminal sections are used to raise a central section in the manner illustrated in 95 Fig. 4.

I claim as my invention—

1. A floating dock comprising central and terminal sections, each U-shaped in cross-section, said terminal sections each having a 100 tongue adapted to extend between the side walls of another section and rest on said section between said walls.

2. A floating dock comprising central and terminal sections, each U-shaped in cross- 105 section, and adapted to be securely fastened together to form a rigid structure, each terminal section having a projecting tongue adapted to enter between the side walls of another section, and each section of the dock 110 being constructed with water-tight compartments, and having a lifting power such that any two sections are capable of lifting and supporting any one of the other sections.

In testimony whereof I have hereunto subscribed my name.

LYONEL EDWIN CLARK.
